(57) **CLAIM**

I claim the ornamental design for a gutter for patio roofing system, as shown and described.

DESCRIPTION

FIG. 1 is a bottom, front isometric view of a gutter for patio roofing system showing my new design;

FIG. 2 is a top, front isometric view thereof;

FIG. 3 is a front elevation view thereof;

FIG. 4 is a right side elevation view thereof;

FIG. 5 is a top plan view thereof;

FIG. 6 is a top, rear isometric view thereof; and,

FIG. 7 is a rear elevation view thereof.
